UNITED STATES PATENT OFFICE.

LEWIS DALE BROWN, OF BUTLER, PENNSYLVANIA.

MANUFACTURE OF DRILLS OR BITS.

No. 894,589.

Specification of Letters Patent.

Patented July 28, 1908.

Application filed July 26, 1907. Serial No. 385,664.

To all whom it may concern:

- Be it known that I, LEWIS DALE BROWN, a citizen of the United States of America, residing at Butler, in the county of Butler and State of Pennsylvania, have invented certain new and useful Improvements in the Manufacture of Drills or Bits, of which the following is a specification, reference being had therein to the accompanying drawing.
- 10 This invention relates to improvements in the manufacture of drills and bits, and more particularly to a novel mold for forming drills and bits used for drilling wells.
- 15 The invention has for its object to provide a durable mold that can be used for forming a plurality of drills or bits, the mold being constructed into two parts, whereby the finished product can be easily and quickly removed from the mold.
- 20 The detail construction entering into my invention will be presently described, and then specifically pointed out in the appended claims.

Referring to the drawings forming a part 25 of this specification, Figure 1 is a vertical sectional view of a mold, Fig. 2 is an elevation of one half thereof, and Fig. 3 is a vertical sectional view of the parts of a mold separated.

30 To put my invention into practice, I construct my improved mold for drills and bits of two parts 1 and 2, these parts being formed of metal. To produce parts 1 and 2 I use an ordinary drill or bit 3 as a pattern and suitably support the same, in an opening 4 into which molten metal can be poured. The opening 4 is formed in sand or similar material, and after the opening has been filled with molten metal, and the metal permitted 35 to cool, the pattern and the metal surrounding the same are removed from the opening. The metal surrounding the pattern is then

drilled to provide transverse openings 5 and is sawed or otherwise cut to form the parts 1 and 2. It is therefore obvious that after 45 the parts have been formed, that the pattern 3 can be easily removed. The metallic parts 1 and 2 are then connected together by fastening means (not shown) passing through the transverse openings 5, thus providing a 50 concavity 6 into which molten metal can be poured to produce a drill or bit conforming in all respects to the pattern 3.

The mold formed by the parts 1 and 2 can be used numerous times for forming drills or 55 bits, and while I have not herein specified any material for preventing the pattern or the product from adhering to the sides of the mold, it will be understood that a suitable material can be employed for this purpose. 60

It will thus be observed that I have devised a simple and inexpensive mold that can be roughly handled without being injured, the mold being designed to produce a 65 drill or bit that can be used for the purpose for which it is intended.

Having fully described my invention, what I claim and desire to secure by Letters Patent is:—

The herein described mold composed of 70 opposite similar half-sections each provided on the inner face with a pattern cavity, each half of the mold provided with transverse apertures located approximately midway the ends of the mold sections and on opposite 75 sides of the pattern cavity to receive means for securing the sections together.

In testimony whereof I affix my signature in the presence of two witnesses.

LEWIS DALE BROWN.
